VEHICLE END FRAMING

William H. Mussey and Martin P. Blomberg, Chicago, Ill., assignors to Pullman-Standard Car Manufacturing Company, Chicago, Ill., a corporation of Delaware

Original application June 17, 1933, Serial No. 676,265. Divided and this application June 14, 1934, Serial No. 730,610

13 Claims. (Cl. 105—402)

This application is a division of our copending application Serial No. 676,265, for Light-weight railway car, filed June 17, 1933.

The invention relates generally to metallic 5 railway car construction and more specifically to passenger train vehicles fabricated of aluminum or its alloys.

The principal object of the invention is the 10 provision of a vehicle end framing structure of maximum strength and of minimum weight.

A particular object is so to dispose and connect the individual stress members entering into the end frame assembly as to enable the structure 15 as a unit to distribute shocks of impact, imposed thereon by impacts and the normal surging and lagging action of connected cars in a train, to all of the respective roof, side wall and underframe stress transmitting members equally.

An important object is to provide anti-telescop- 20 ing end wall posts of tubular construction adapted for wedging connection with the end sill casting of the underframe.

The foregoing and other objects are attained 25 by the construction illustrated in the accompanying drawings, in which

Figure 1 is an end elevational view showing the front vestibule end wall with a portion thereof broken away to expose the car body end wall and framing details;

30 Figure 2 is a partial plan of the vestibule having a portion of the roof broken away to show some of the framing details of the body end wall and vestibule end wall;

Figure 3 is a vertical, longitudinal section thru 35 the vestibule of the car taken on line 3—3 of Figure 1, showing the method of anchoring vestibule anti-telescoping posts to the buffer end sill;

Figure 4 is a vertical, transverse section thru 40 the anti-telescoping post anchorage in slightly modified form and taken on line 4—4 of Figure 5;

Figure 5 is a vertical, longitudinal section thru 45 the same taken on line 5—5 of Figure 4 showing the post filler and wedge anchor; and

Figure 6 is a bottom, plan view of the same.

45 In the drawings, only that portion of a railway car 10 adjacent a vestibule thereof is shown, the end of which, as best indicated in Figure 1, is covered by wall sheathing side sheets 12 secured to the hollow posts 249 and vestibule 50 corner posts 269, buffer end sill 18 and roof end carline 190, and by intermediate sheets 11 secured to the roof end carlines and upper ends of the hollow posts 249, as shown in Figure 3. The posts 249 are formed with portions of their 55 upper ends cut away and tapered as at 270 in

Figure 3 to permit the driving of rivets 271 connecting adjacent wall sheets 11 and 12 to the posts at that point, the remaining portions of wall sheets 12 being secured by machine screws 272 tapped into said posts. These sheets are 5 further secured to the posts by vertically disposed angle members 273 extending along the inner faces of the sheets and one side of the posts and riveted to both to insure proper stability of the wall structure at the diaphragm position. 10 The diaphragm 8 is secured by the usual attaching angles 274 also screwed to these posts. The car vestibule 15 is closed by the usual side doors 4 opening inwardly against the car end wall and by platform trap doors 5 covering the step 6 and adapted to be raised against the vestibule doors 15 when open.

In the present embodiment, the posts 249 are 20 tubular and entered in pockets 253 in the buffer end sill 18, as best shown in Figures 4 thru 6. In their preferred form, the posts 249 are made 25 up of two complementary channel-shaped webs 254 and 255, the one nested within its companion member with their flanges overlapped and secured together, preferably by welding. 25

The posts are made larger at their base and tapered thence upwardly and secured to the roof end carline 190 as indicated in Figure 3 and are shown with their inner faces 256 inclined with respect to adjacent inner walls 257 of respective 30 pockets 253 to provide a wedge-shaped opening 258 therebetween adapted to receive a locking wedge 259 designed to prevent withdrawal of the posts from their pockets and develop the full strength of the posts to resist thrusts of impact 35 from the invading car at points above the vestibule platform.

To preserve the contour of the posts at their lower ends under impact pressures and provide 40 the maximum resistance to bending at the buffer end sill, the posts are fitted at their lower ends with tubular filler blocks 260 conforming to the contour of the posts and adapted to be entered between the sides thereof after the posts have been positioned on the car with their lower ends 45 inserted in the buffer end sill pockets 253 and before the locking wedges 259 have been driven. To facilitate the assembling of posts and fillers with the buffer end sill, the post pockets 253 at their lower wall peripheries are formed with in- 50 wardly projecting ledge portions 261 along three sides of the openings upon which the posts are adapted to be supported. The filler blocks are formed for telescopic engagement with the posts and secured by bolts 262 extending transversely 55

thru opposite walls 263 of the filler, webs 254 and 255 of the posts, and webs 264 and 265 of the buffer and sill 78, as best shown in Figures 4, 5 and 6.

It will be noted that the filler blocks 260 extend 5 with their bodies well above the upper level of the buffer end sill to provide substantial reinforcement for the posts against bending and possible shear at the platform. To insure accurate registration of the bolt openings for the securing bolts 10 262 and prevent upward movement of the filler blocks 260 beyond their assigned positions within the zone of the buffer end sill during the operation of assembling, the blocks are formed with stop flanges 266 extending along their lower wall 15 edges at three of the sides of the block corresponding to the position of the post supporting ledges 261 on the buffer end sill so that such flanges will engage the undersides of the post ledges to permit application of the block supporting bolts. 20 With the filler blocks in position within the posts and secured, they function as backing blocks to preserve the contour of the relatively light posts under pressure of the wedges 259 driven in between the inner walls 257 and adjacent inclined 25 faces 256 of the posts.

It will be noted that the wedges 259 have their post-adjacent faces conforming to and engaging the sloping post faces 256 and their opposite faces parallel to and engaging the vertical pocket 30 walls 257 and are held from displacement by welding the upper edges thereof to the posts and/or buffer end sill, as shown at 261, and at their lower edges to the buffer end sill as best indicated at 268 in Figure 5. By virtue of the construction described, the vestibule end posts 249 are held interlocked with the buffer end sill against withdrawal and shear under impact, and because of the use of post filler blocks designed to receive the thrust of the locking wedges 259, the relatively light post 35 sections are held from distortion under the crushing pressures developed at the post bases during car movement.

The end sill 71 comprises, in the present embodiment a continuous anti-telescoping plate portion 221 extending between and secured to the inwardly projecting upper flanges 69 of the side sills, a pair of U-shaped transverse members having base plate portions 222 and front and rear up-standing flanges 223 and 224, respectively, extending from opposite sides of the center sill 79 to the side sills 21. The rear flanges 224 are bent rearwardly along their upper margins to provide attaching and supporting flanges 225 for adjacent edge of the anti-telescoping plate 221 45 which bridges the gap between the flanges 225 across the center sill and connects the U-shaped members to unify the end sill assembly. These members are further reinforced transversely of the car by continuous, angular members 226 secured to the upper side of the anti-telescoping plate 221 to which and the underlying supporting flanges 225 they are secured by rivets 227, as best shown in Figure 3.

The U-shaped members are connected to the 50 draft sills 85 by connections 228 or otherwise and supported at their opposite ends upon the inwardly projecting lower flanges 70 of the side sills. The U-shaped members are further stiffened by underlying cover plates 229 secured to 55 base plates 222 of the members and preferably extending from the draft sills 85 to the side sills. These cover plates are of substantial width and formed with downwardly extending flanges 230 at their inner ends for connection to the draft sills 60 and secured to the underside of inwardly and out-

wardly projecting lower flanges 70 and 71 of the side sills by rivets 231 whereby such plates would function as gussets to preserve the rectangular relation between end sill and draft and side sills although separate gussets at draft and side sill positions would meet the requirements in cases where the intermediate portions of the end sill members thus connected do not require the reinforcement afforded by the extended cover plates shown. 10

The continuity of the outer flanges 223 of the end sill U-shaped members is established by angle members 232 extending across the center sill and connecting the respectively adjacent ends of flanges 223 to which they are secured by rivets 15 233 as indicated in Figure 1, the member 232 serving also to support the inner edge of platform plate 94 between the step risers 95. The anti-telescoping end sill plate 221 is further stiffened along its rear margin by flanges 189 extending 20 transversely of the car between center and side sills and between side walls 81 of the center sill top chord 79.

The door posts 234, diagonal braces 235 and intermediate stiffening posts 236 of the end wall 25 framing assembly are all of them framed into the end sill with their respective lower ends between the upstanding front and rear flanges 223 and 224 of the U-shaped members. The door posts 234 are preferably channel-shaped with their flanges 30 riveted to end sill flanges 223 and 224. The diagonal braces, however, are of less depth and secured to front flanges 223 of the end sill members, while the intermediate stiffening posts are of less depth than the other posts and secured to 35 the rear flanges 224 of the end sill members, but, in the present embodiment, only the post members 234 and 236 are extended to connect with adjacent carlines 59 although the diagonals 235 may likewise be extended to connect with said 40 carlines, if desired. The interior wall sheets 237 which are interposed at this point extend downwardly upon opposite sides of the door opening 238 to the floor 76 and to a point above the door opening to define the door lintel 239, the door 45 and intermediate posts being secured to said sheets between floor and carlines, as best shown in Figures 1 and 3.

At the end wall position, the side plates 23 support an end plate 240 extending transversely 50 between and connecting the ends of the side plates and adjacent ends of carlines 59 and uniting adjacent ends of the post and brace members of the end framing, as shown in Figures 1 and 3. The end plate 240 is in the form of a channel 55 with its web 241 extending vertically and its upper and lower flanges 242 and 243 outwardly, the lower flange 243 serving as an attaching member for the vestibule ceiling sheets 244 and securing flange 245 for the outer lintel finishing sheets 246. 60

The end plate channel provides a connection 247 for the inner ends of longitudinal members 248 having their opposite ends secured to vestibule end posts 249, whereby shocks of impact upon said posts or imposed by the action of associated upper buffering mechanism 250 during normal surging movement of connected cars in a train are transmitted to the end plate and by it to the side plates 23. The post members 234 and diagonal braces 235 are also secured at their upper ends 70 to web 241 of the end plate 240 which thus acts to rigidify the whole end framing assembly at the roof line, rivets 251 securing the door posts and connecting the diagonal braces to the end plate and the sheathing sheets 252. 75

The braces 235 extend from adjacent the door posts at their lower ends to adjacent the side plates at their upper ends so that in the event of collision and collapse of the end framing assembly, possible telescoping of the cars would be prevented by the gathering-in of the side plate longitudinals with their connecting end plates 240 into the path of the invading car to check its progress to the car interior. The gathering-in of the end framing assembly would result only in the event of the complete destruction of anti-telescoping vestibule end posts 249 under thrust of the invading car.

The roof structure is arched between the side plates 23 and secured as a unit to underlying channel-shaped side plates 22 by rivets 51 or otherwise to prevent displacement thereof and insure further cooperation with the side wall structure. The side plates 23 are also preferably channel-shaped with a pair of upstanding outer and inner flanges 52 and 53 with the connecting webs 54 projected outwardly beyond flange 52 and flanged downwardly at 55 to provide a watershed spaced outwardly from the outer flange of the side plate channel 22 beneath and a securing means for the curved roof plates 24 connected thereto by rivets 57. The roof plates 24 are rigid and extend upwardly from the side plate flanges 55 and inwardly for connection to intermediate and relatively light roof sheets 58.

The roof plates and sheets are reinforced by carlines 59 extending transversely of the car and supported at their ends upon side plates 23 and held from displacement by the upstanding flanges 52 and 53 to which and the web 54 they are secured by rivets 60 as best shown in Figure 3. The rigid roof plates 24 and the relatively light intermediate roof sheets 58 are preferably joined by riveting as indicated at 61 or by welding, and are further braced and secured at side plate flanges 52 having thickened marginal portions 62 to which the roof plates are connected by rivets 60, the enlarged edges conforming to the curvature of and providing additional bearing area for the plates.

Because of the unitary character of the extruded longitudinal stress members of the side plates, the joining together of the several separate members heretofore making up such assembly is avoided and the members shaped to conform to associated parts, as will be evident from an inspection of the side plate member 23 having an outer flange 52 in addition to the inner flange 53 whereby the ends of carlines 59 are nested between such flanges 52 and 53 as in a pocket, the outer flange also providing a bearing and securing means for the curved roof stress plate 24 in planes inwardly of the depending eaves flange 55 so that the assembly would function as a column in buffing.

60 What we claim is:

1. In a railway car, a vestibule end framing including a buffer end sill having web portions defining thru openings vertically of the sill, hollow end posts entered in said openings, and means for locking said posts to said sill.

2. In a railway car, a vestibule end framing including a buffer end sill having web portions defining thru openings vertically of the sill, hollow end posts entered in said openings, and means including wedge members for locking said posts to said sill.

3. In a railway car, a vestibule end framing including a buffer end sill having web portions defining thru openings vertically of the sill, hollow end posts entered in said openings and

formed with portions inclined with respect to and receding from a wall of said opening, and wedge members entered in the space between the posts and said walls secured to said sill for locking the posts within the sill openings. 5

4. In a railway car, a vestibule end framing including a buffer end sill having web portions defining thru openings vertically of the sill, hollow end posts supported in said openings and formed with portions thereof receding from a wall of said openings, wedge means for locking said posts to the sill entered in the space between the respective posts and said walls, and filler blocks secured to and telescopically engaging said posts within the zone of said wedge means and sill. 15

5. In a railway car, a vestibule end framing including a buffer end sill having openings vertically of the sill, hollow end posts supported in said openings, means in said openings for supporting said posts, and means for locking said posts to the sill including filler blocks telescopically engaging said posts and secured thereto and the sill and formed with limiting flanges on more than one and less than all of its lower peripheral sides adapted for engagement with said post supporting means. 20

6. In a railway car, an end framing including an end plate and sill extending transversely of the car with vertical door posts and downwardly and inwardly extending braces connecting said plate 30 and sill, a second end framing spaced outwardly from the first named framing to provide a vestibule between them and including a buffer end sill member extending transversely of the car and providing extensions inwardly of said sill for connection with the end sill of the first framing and support the platform between, vestibule corner posts, hollow end posts interlocked with said buffer end sill, a roof carline member connecting said corner posts, and vestibule wall plates connecting 35 said posts and carline.

7. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically 50 of said sill, hollow end posts entered in said openings, means for locking said posts to the sill, connections between said sill and the end sill of the first framing providing support for the platform between, vestibule corner posts, a roof carline member connecting said corner posts, and vestibule wall plates connecting said posts and carline. 55

8. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically 60 of said sill, hollow end posts entered in said openings, wedge members for locking said posts to the sill, connections between said sill and the end sill of the first framing providing support for the platform between, vestibule corner posts, a roof carline member connecting said corner posts, and vestibule wall plates connecting said posts and carline. 65

9. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically of said sill, hollow end posts entered in said openings and formed with portions inclined with respect to and receding from a wall of said openings, and wedge members entered in the space between said posts and the walls and secured to said sill for locking the posts within the sill openings, connections between said sill and the end sill of the first framing providing support for the platform between, vestibule corner posts, a roof carline member connecting said corner posts, and vestibule wall plates connecting said posts and carline.
10. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically of said sill, hollow end posts entered in said openings and formed with portions inclined with respect to and receding from a wall of said openings, wedge members entered in the space between said posts and the walls, connections between said sill and the end sill of the first framing providing support for the platform between, vestibule corner posts, a roof carline member connecting said corner posts, and vestibule wall plates connecting said posts and carline.
11. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically of said sill, hollow end posts entered in said openings and formed with portions inclined with respect to and receding from a wall of said openings, wedge members entered in the space between said posts and the walls secured to said sill for locking the posts within the sill openings, filler

blocks secured to and telescopically engaging said posts within the zone of said wedge members and sill, connections between said sill and the end sill of the first framing providing support for the platform between, vestibule corner posts, a roof carline member connecting said corner posts, and vestibule wall plates connecting said posts and carline.

12. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically of said sill, hollow end posts entered in said openings and formed with portions inclined with respect to and receding from a wall of said openings, wedge members entered in the space between said posts and the walls, filler blocks secured to and telescopically engaging said posts within the zone of said wedge members and sill, connections between said sill and the end sill of the first framing providing support for the platform between, vestibule corner posts, a roof carline member connecting said corner posts, and vestibule wall plates connecting said posts and carline.

13. In a railway car, an end framing including an end plate and an end sill extending transversely of the car with vertical door posts and downwardly and inwardly extending braces connecting said plate and sill, a second end framing spaced outwardly from the first named framing to provide a vestibule between them and including a buffer end sill member extending transversely of the car having thru openings vertically of said sill, hollow end posts entered in said openings, ledge means in said openings for supporting said posts, and means for locking said posts to the sill including filler blocks telescopically engaging said posts and secured thereto and the sill and formed with limiting flanges on more than one and less than all of its lower peripheral sides adapted for engagement with said post supporting means, connections between said sill and the end sill of the first framing providing support for the platform between, vestibule corner posts, a roof carline member connecting said corner posts, and vestibule wall plates connecting said posts and carline.

WILLIAM H. MUSSEY.

MARTIN P. BLOMBERG.
